UNITED STATES PATENT OFFICE.

ROGER W. MCBRIEN, OF ALTON, ILLINOIS.

THERMOSTATICALLY-OPERATED ELECTRIC SWITCH.

Application filed May 4, 1927. Serial No. 188,728.

My invention has relation to improvements in thermostatically operated electric switches and consists in the novel features of construction more fully set forth in the 5 specification and pointed out in the claims.

The present invention is an improvement over that shown in my co-pending application, Serial No. 43,785 filed July 15, 1925, in that certain features to appear more fully 10 hereinafter have been embodied to render more expeditious the operation of the thermostatic switch. As in the application aforesaid, a body of mercury is maintained in contacting relation with two conductors of a 15 circuit by means of a plug of wax which is caused to be displaced under the application of heat and permit the mercury to be dislodged, thereby opening that circuit and closing a second circuit.

20 The principal object of the present invention is to provide a thermostatically operated switch wherein suitable means is embodied for speeding the response of the switch to changes in temperature therein. Other advantages are that the switch is comparatively simple and may be cheaply manufactured and may be used repeatedly. These advantages as well as others possessed by the invention will be better apparent from a detailed description of the invention in connection with the accompanying drawings, in 25 which:—

Figure 1 represents a panel on which is mounted my improved thermostatic switch 30 together with a signal lamp and alarm, an electrical circuit containing this switch being shown more or less diagrammatically; Fig. 2 is a horizontal cross-section taken on the line 2—2 of Fig. 1; and Fig. 3 is a side elevation of the panel and the switch which 35 is mounted thereon.

Referring to the drawings, P represents a panel made of a suitable insulating material to which is fixed in spaced relation three 40 clips 1, 2 and 3 to the first of which is connected a conductor 4, to the second a conductor 5 and to the third a conductor 6. My improved thermostatic switch comprises a tubular casing or receptacle 7 of suitable insulating material, the ends of which are covered with metallic caps 8 and 9 and the center being provided with a metallic band 10. Shoulders *a*, *b* are formed on the inner surface of the casing 7, a short distance inwardly 45 from the ends thereof, and metallic closure members or partitions 11 and 12 are inserted

in the ends of casing 7 and caused to set against the shoulders *a* and *b* respectively. A short neck 13 extends inwardly from each closure member and the opening 14 in the 50 neck and member is traversed by a stem 15 having a valve 16 formed on its inner end, and a short cross piece 17 on its outer end whereby the stem 15 is prevented from passing through the opening in the neck 13. The 55 head 16 of the stem 15 operates as a valve and the inner end of neck 13 as a valve seat therefor for a purpose that will be explained in connection with the operation of the device.

A stud 17 projects into the casing 7 from the center band 10, said stud having electrical connection with the band 10 and carrying a cross piece 18 on its inner end together with a cooperating spring clip 19 for supporting a coil of wire 20 within the casing, the ends of said coil 20 being equally spaced a short distance from the adjacent members 11, 12. There are coils of wire 21 and 22 disposed within the spaces between member 11 60 and cap 8, and member 12 and cap 9 respectively, these coils making electrical connection with the caps and members with which they are in contact. A body of mercury 23 is placed within the casing 7 and a plug of wax 24 is arranged to confine said body of mercury at one end of the casing 7 so that it will make contact with either member 11 or 12 and one end of the coil 20.

The thermostatic switch is connected into 65 the circuit of any electrically operated apparatus (a lamp 25 representing such apparatus in the present instance), said circuit being completed by a wire *y*. A signal lamp 26 and alarm 27 are connected in parallel 70 with said circuit by being connected between conductors 6 and wire *y*.

The operation of my improved thermostatic switch may now be described as follows:—

In the normal operation of the device, the current will flow from the conductor 5 through the clip 2, coil 20, mercury 23, partition 11, conductor 21, conductor 4, thence throughout the circuit and conductor *y*. 75 Should there be a short circuit or should there be an excessive load on the circuit, the excess current flowing through the coil 20 will cause the same to become heated as will also the coil 21, the heating of the coil 20 softening 80 the wax 24 and the heating of the coil 21 increasing the pressure of the gas therein 110

which will be vented through the opening 14 exerting pressure on the mercury 23 and wall 24 so that when the same shall have been softened sufficiently, a core (represented by the dotted lines Fig. 1) will be dislodged from the wall of wax allowing the mercury to escape from its confinement and accumulate on the partition 12. Since the valve 16 closes the opening 14 in the partition 12, the mercury 10 will not enter into the space below the partition, but will close the circuit between the coil 20 and partition 12 thereby causing a current to flow through the circuit comprising lamp 26 and alarm 27 and announcing the fact that 15 something is wrong in the power circuit.

The advantage of the vent in the partitions 12 and 11 is that the pressure created therein and imparted to the wall 24 will provide an escape for the mercury much more quickly 20 than would be the case if no pressure were exerted against the wall. Thus, it will be seen that I have provided a thermostatic switch that is not only certain in its operation but is also quick to respond to the conditions causing 25 it to operate.

Having described my invention, I claim:

1. A thermostatic switch comprising a receptacle of a non-conducting material, a cap on one end of said receptacle, a perforated 30 partition having electrical conductivity within the receptacle and spaced from said cap, a conductor within the casing, means for connecting one end of said conductor with a circuit outside the receptacle, a second conductor disposed between the partition and 35 cap and having electrical connection with the

partition, means for connecting one end of said conductor with said circuit, a fusible insulating wall within the receptacle and spaced from the partition, and a fluent conductor confined between the partition and wall and having 40 electrical connection with the partition.

2. A thermostatic switch comprising a receptacle of a non-conducting material, a cap at one end of said receptacle, a conductor traversing said receptacle and forming one element of an electric circuit, a fusible insulating wall in contact with said conductor, a fluent conductor held in place by said wall, means within the receptacle for exerting pressure on said wall to dislodge the same and liberate the fluent conductor when the first mentioned conductor becomes unduly heated.

3. A thermostatic switch comprising a receptacle of a non-conducting material, a metallic cap disposed on each end of said receptacle, one of said caps having connection with a power circuit and the other with an alarm circuit, a conductor within the receptacle and spaced from said caps, said conductor having connection with both circuits, a fusible wall in the receptacle, a fluent conductor adapted to be sustained by the fusible wall to close the space between the conductor and one cap, and means for effecting a dislodgment of the wall with excessive temperature rise in the receptacle to cause the fluent conductor to close the space between the conductor and the other cap.

In testimony whereof I hereunto affix my 70 signature.

ROGER W. McBRIEN.
